(57) **CLAIM**

The ornamental design for a styling comb, as shown and described.

DESCRIPTION

FIG. 1 is a front, left and top perspective view of a styling comb, showing my new design;

FIG. 2 is a rear, right and bottom perspective view thereof;

FIG. 3 is a perspective view of the styling comb shown in a new configuration;

FIG. 4 is another perspective view thereof;

FIG. 5 is a front view of the styling comb shown in the FIG. 1 configuration;

FIG. 6 is a rear view thereof;

FIG. 7 is a left side view thereof;

FIG. 8 is a right side view thereof;

FIG. 9 is a top plan view thereof;

FIG. 10 is a bottom plan view thereof; and,

FIG. 11 is an enlarged view of a portion of the styling comb shown within the area designated as 11 in FIG. 3.

The broken lines shown in the drawings illustrate portions of the styling comb that form no part of the claimed design. The dot-dash broken lines encircling portions of the styling comb in FIG. 3 and illustrated in the enlarged view in FIG. 11 form no part of the claimed design.
